M. L. BRAMSON,
SPRING, PARTICULARLY FOR USE IN PERCUSSION TOOLS.
APPLICATION FILED NOV. 2, 1920.

1,400,019.

Patented Dec. 13, 1921.

Inventor -
Morgan Louis Bramson
By - B. Amger, Atty.

UNITED STATES PATENT OFFICE.

MOGENS LOUIS BRAMSON, OF STAFFORD, ENGLAND.

SPRING, PARTICULARLY FOR USE IN PERCUSSION-TOOLS.

1,400,019.

Specification of Letters Patent. Patented Dec. 13, 1921.

Application filed November 2, 1920. Serial No. 421,405.

To all whom it may concern:

Be it known that I, MOGENS LOUIS BRAMSON, a subject of the King of Denmark, and resident of Stafford, in the county of Stafford, England, have invented certain new and useful Improvements in and Relating to Springs, Particularly for Use in Percussion-Tools, (for which I have filed applications in Great Britain No. 17,351, July 10, 1919; Belgium Oct. 8, 1920; France Oct. 6, 1920; Denmark Oct. 1, 1920; Holland Oct. 2, 1920; Norway Sept. 30, 1920; Spain Oct. 5, 1920; Sweden Oct. 1, 1920,) of which the following is a specification.

This invention relates to resonators. In many instances and particularly in the case of percussion tools it is necessary to suspend a reciprocating mass between springs so arranged and adjusted that a condition of resonance is established between the mass and the springs.

Hitherto this has been effected by suspending the mass between metal springs of suitable form but it has been found that in percussion tools for instance, where the mass is subjected to a high rate of reciprocation the springs frequently break.

We have proved by experience that it is possible to substitute for these metallic springs, other springs formed or constituted by liquid columns or capacities and the desired resonance conditions can be obtained by adjusting the respective areas upon which the liquid operates, and the volumes of the capacities or springs to fulfil the conditions requisite for a resonator.

The underlying principle of the present invention is the substitution for the metallic springs hitherto employed, liquid springs, and the invention consists broadly in suspending the reciprocating mass between columns of liquid.

It follows that the invention depends for its success upon the fact that liquids are not incompressible but elastic.

Although capable of application to other uses where it is required to provide a spring suspension for a reciprocating mass the invention is particularly applicable to percussion tools for use in wave transmission systems, the general principles of which are now well known and are outlined in the specification of Letters Patent No. 9029 of 1913.

In carrying the invention into practice,

three fundamental conditions must be observed: Firstly, there must be resonance between the reciprocating mass and the capacities. That is to say, the reciprocating mass and the capacities must be in a state of resonance and satisfy the equation $LC\alpha^2=1$ when L =co-efficient of inertia, C =co-efficient of capacity and α =the angular velocity in radians per second. Secondly, the mean pressure in the line must be balanced by the maximum pressure on the front capacity acting on their respective areas.

This second condition is only strictly true in cases where there is no initial pressure in the system but where there is an initial pressure, as is usually the case in practice, this initial pressure has to be taken into account and it is a more accurate statement for all conditions to say that the force exerted by the mean pressure in the line acting on its area of the reciprocating mass plus the force exerted by the minimum pressure in the rear capacity acting on its area of the reciprocating mass must equal the force exerted by the maximum pressure in the front capacity acting on its area of the reciprocating mass.

Thirdly, the mean pressure in the line and the pressures in the two capacities must all be equal when the apparatus is in operation. The first and second of these conditions is in accordance with the same principles as when metallic springs are used, and are obtained in the same way. The third condition is necessary because leakage will, in any case, make the mean pressures equal and therefore if they are not equal when the apparatus is working, it will cease to work when they are.

In the accompanying drawing:—

Figure 1 is a longitudinal section of a device illustrating my invention diagrammatically.

Fig. 2 is a longitudinal diagrammatic section illustrating the application of this invention to a riveting hammer.

Referring to the drawings a designates the reciprocating mass, b designates the inlet or line connection from a wave transmission generator, b^1 is the area of the reciprocating mass a upon which the pressure in the line operates, c is the front capacity, the annulus c^1 is the area upon which the pressure in this front capacity acts, d is the rear capacity and the annulus d^1 is the area

upon which the pressure in this rear capacity acts. The blow or energy is imparted by the reciprocating mass at the end *e*.

In carrying the invention into practice 5 the arrangements must be such that the force exerted by the maximum pressure in the rear capacity *d* acting on the annulus *d*¹ is .57 of the force exerted by the maximum pressure in the front capacity *c* acting on 10 the annulus *c*¹.

The operation may be stated in popular 15 language as follows:—The pressure waves enter at the inlet or line connection *b* and the pressure rises and falls from zero to maximum in accordance with a given frequency in the manner now well known. The blow commences to be struck, or, in other words, the energy commences to be imparted when the reciprocated mass *a* reaches its foremost 20 position—indicated in the diagram by the dotted line. This occurs when the pressure in the line *b* has risen from zero to its mean pressure. This blow continues, or in other words, the energy continues to be imparted 25 until the pressure in the line *b* has risen to its maximum value and fallen again to its mean value. The movement of the mass *a* in the forward direction into the front capacity *c* has caused the pressure in the capacity *c* to rise owing to the fact that there 30 is no displacement of the liquid, and when the line pressure falls to its mean value the pressure in the capacity *c* acting on the annulus *c*¹ exerts a force which just balances 35 the opposing force exerted by the mean pressure in the line *b* acting on the area *b*¹ plus the force exerted by the pressure in the rear capacity *d* acting on the annulus.

Assuming that there is no initial pressure 40 in the system there will be no pressure in the capacity *d* at this instant but assuming that there is an initial pressure in the system the pressure in the capacity *d* will be this initial pressure only, *i. e.* the pressure in the capacity *d* will be at its minimum value.

Immediately the line pressure at *b* falls 45 below its mean value it follows that the force exerted upon the reciprocating mass in the rearward direction will overcome the 50 force exerted upon it in the forward direction and the mass *a* will be forced back until the pressure in the line *b* again rises when the cycle is repeated.

It will be understood that the above represents the action of one period in the wave 55 and the action is repeated with the wave frequency. That is to say, assuming a wave frequency of 2,300 periods per minute, which is a usual frequency, the action will be repeated 2,300 times per minute. The application of the invention to percussion tools therefore becomes apparent and it will be clear that when the invention is applied to a riveting or calking hammer the handle may be utilized to provide the necessary volume 60 for the capacities, and in a rock-drill the body can be utilized for this purpose.

What I claim and desire to secure by Letters Patent is:—

1. A resonator comprising a reciprocating mass suspended between liquid columns operating as springs so arranged and adjusted that a condition of resonance is established between the mass and the liquid springs substantially as specified.

2. A resonator comprising a reciprocating mass having an area subject to the pressure of a liquid column in one direction and an area subject to the pressure of a liquid column in the opposite direction the respective 80 areas and pressures being so related that a condition of resonance is established between the mass and the liquid columns which operate as springs substantially as specified.

3. A percussion device comprising a reciprocating mass adapted periodically to impart energy at one position and to have energy periodically imparted to it at another position, and liquid capacities between which the mass is suspended the arrangement being 90 such that the reciprocating mass and the springs constituted by the liquid columns are in resonance substantially as specified.

4. A wave transmission percussion device comprising a reciprocating mass adapted 95 periodically to impart energy at one position and to be subject to the alternating pressure of a wave transmission generator at another position, and a front capacity and a rear capacity between which the mass is mounted in 100 spring suspension so that the mass and the springs constituted by the capacities are in resonance substantially as specified.

Signed at London, England, this twentieth day of October, 1920.

MOGENS LOUIS BRAMSON.
